Primary Examiner — Cynthia M. Chin

(57) **CLAIM**

The ornamental design for a toy car, as shown and described.

DESCRIPTION

FIG. 1 is a perspective view of a toy car showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged partial view taken from a car body shown in FIG. 1;

FIG. 10 is an enlarged partial view taken from a front wheel shown in FIG. 1;

FIG. 11 is an enlarged partial view taken from the car body shown in FIG. 2;

FIG. 12 is an enlarged partial view taken from the car body shown in FIG. 3; and,

FIG. 13 is an enlarged partial view taken from the car body shown in FIG. 3.

The broken lines are for the purpose of illustrating portions of the article that form no part of the claimed design. The dash-dot broken lines represent the boundaries of the enlarged partial views of FIGS. 9-13 and form no part of the claimed design.

1 Claim, 13 Drawing Sheets
